UNITED STATES PATENT OFFICE.

PIETER DE LANGE AND ROBERT AERNOUT BARON VAN LYNDEN, OF UTRECHT, NETHERLANDS, ASSIGNEES TO NAAMLOOZE VENNOOTSCHAP DE NEDERLANDSCHE THERMO-TELEFOON MAATSCHAPPIJ, OF UTRECHT, NETHERLANDS, A CORPORATION OF NETHERLANDS.

THERMIC TELEPHONE.

1,200,470.

Specification of Letters Patent.

Patented Oct. 10, 1916.

Application filed November 4, 1915. Serial No. 59,621.

To all whom it may concern:

Be it known that we, PIETER DE LANGE and ROBERT AERNOUT BARON VAN LYNDEN, both subjects of the Queen of the Netherlands, 5 and residing at Utrecht, in the Netherlands, have invented a new and useful Thermic Telephone, of which the following is a specification.

This invention relates to thermic telephones, and has for its object to provide a thermic telephone in which the intensity of reproduction of the sound can be regulated as required. This object is attained by the thermic telephone being constituted of heating conductor groups arranged one above the other or side by side in one and the same casing, secured to detachable supports and electrically connected together, the number of the said groups being calculated to 15 suit the requirements of the telephone user. Owing to this arrangement, the aurist can prescribe for his patient, a hearing device provided with the thermic telephone according to this invention, in the exact manner 20 as an oculist prescribes to his patient spectacles with given lenses.

An embodiment of our invention is illustrated by way of example in the accompanying drawing which shows the improved 25 thermic telephone in vertical section, partly in elevation, drawn to an enlarged scale.

The thermic telephone illustrated comprises a tubular casing 1 which is closed at both ends by means of cap or plug-like 30 covers 2 and 3 screwed into it. Within the tubular casing, heating conductor units are accommodated, each unit consisting of a suitable support 4 fitting the interior of the casing, and a group of heating conductors 5 mounted on each support 4. These heating conductor units are loosely inserted into the casing 1 and held at the necessary distance apart, by means of preferably exchangeable 35 distance rings 6. For the passing of the sound waves, each of the supports 4, with the exception of the lowest one, is provided with an opening 7 preferably arranged in the center. The interior of the upper cover 2 forms the sounding chamber 8. The heating conductor group 5 adjoining the sound chamber 8 is covered by an annular protective hood 9 the cross-section of which 40 conforms to that of the arch-shaped con-

ductors. The center 10 of the annular hood 9 forms a sound passage similar to the passages 7. The hood may also be provided at the top with sound openings 11.

The superimposed groups of heating conductors are firmly held in the casing by means of the screw plug 3. This plug supports a disk 12 which in its turn engages the first ring 6 on which rests the first support 4 etc. up to the hood 9 which is held by the edge of cup 8.

The current conductors 13 14 are carried 45 through the central opening 15 of the cover 3 and through the annular disk 12. Their ends are connected to hollow contact studs 16, 17 inserted into the lowest support 4. Pins 18, 19 of the next higher support 4 engage with the bores of the hollow contact studs 16, 17, an electric connection thus being obtained between the two lowest heating conductor groups. The other heating conductor groups 5 are electrically connected 50 together in the same manner.

In the construction illustrated the upper end of the cover 2 is provided with a connecting branch 20 for a flexible tube 21 leading to a sound receiver 22 intended to 60 be introduced into the auditory passage of the human ear. The arrangement might also be made so that the cover 2 itself acts as sound receiver.

The described building up of the heating 65 conductor groups superimposed or arranged side by side in one and the same casing, enables the number of the heating conductors to be modified easily to suit the requirements of the telephone user.

The hood 9 fitting the shape of the arch-shaped heating conductors and adjoining the outer sound chamber 8, not only insures a favorable transmission of the sound waves of the uppermost heating conductor group 90 5, but also protects as far as possible the whole series of the heating conductors from penetration of dust or dirt particles or the like through the opening of cover 2.

The shape and arrangement of the heating conductors, as well as the method of securing them to their supports, is immaterial for the invention. The heating conductor groups may be arranged either in series or in parallel connection, or in mixed connection.

We claim:

1. A thermic telephone, comprising a casing, groups of heat conductors superimposed in said casing, and means for electrically connecting said groups, said groups being adapted to be readily removed from said casing.
2. A thermic telephone, comprising a casing, groups of heat conductors arranged side by side in said casing, and means for electrically connecting said groups, said groups being adapted to be readily removed from said casing.
3. A thermic telephone, comprising in combination, a casing, means for closing both ends of said casing, and a plurality of heating conductor units within said casing, said units being held in position by said means for closing the ends of said casing.
4. A thermic telephone as described, comprising in combination, a casing of tubular shape, a plurality of heating conductor units loosely inserted within said casing, plugs on either end of said casing, said plugs being adapted to hold in position said plurality of heating conductor units.
5. A thermic telephone as described, comprising in combination, a tubular casing, a plurality of heating units loosely fitting into said casing, distance members fitting into said casing and adapted to be placed between two successive units, means for electrically connecting said units, and means for closing the ends of said casing and for firmly holding said units and said distance rings in position.
6. A thermic telephone as described, comprising in combination, a tubular casing, a plug at one end of said casing, a hollow cover at the other end of said casing, an opening in said hollow cover, a plurality of heating conductor units within said casing, each unit consisting of a group of heating conductors and a support therefor, distance rings placed between each two adjoining supports, contact studs on one of said supports and sockets on the adjoining support, and means for connecting the contact studs of the lowest support to the current conductors.
7. A thermic telephone as described, comprising in combination, a tubular casing, a detachable plug for closing one end of said casing and having a passage for the current conductors, a hollow cover detachably secured to the other end of said casing and having a passage for the sound waves, a plurality of superimposed heating conductor units within said casing between said plug and said hollow cover, each of which units consists of a group of heating conductors and a support for the same, said supports being provided with sound passages, distance rings between two adjoining supports, a distance ring beneath the lowest support, a protective hood for the heating conductor group of the top unit, a central sound passage in said hood, means for electrically connecting the heating conductor units, and means for electrically connecting at least one heating conductor unit to the current conductors.
8. A thermic telephone as described, comprising in combination, a casing, a plurality of heating conductor units within said casing, each of which units is adapted to be readily removed from said casing, means for closing the ends of said casing, said means being adapted to hold said plurality of units in position, a passage for the sound waves in one of said means for closing the ends of said casing, a flexible tube communicating with said passage, a receiver at the termination of said tube adapted to be introduced into the human ear, means for conductively connecting said heating conductor units when in position within said casing, and means for conductively connecting at least one of said heating conductor units with the current conductors.
9. In a thermic telephone, in combination, a plurality of heating conductor units each of which is adapted to be readily removed from said casing, means for conductively connecting said units, said means becoming operative on said units being placed in position within the telephone casing, and means for conductively connecting at least one of said units to the current conductors.

In testimony whereof we have signed this specification.

PIETER DE LANGE.
ROBERT AERNOUT BARON VAN LYNDEN.
